UNITED STATES PATENT OFFICE.

IVAN ORNBERG, OF DETROIT, MICHIGAN, ASSIGNOR TO HUPP MOTOR CAR CORPORATION, OF DETROIT, MICHIGAN, A CORPORATION OF VIRGINIA.

FINISH MEMBER.

Application filed May 31, 1927. Serial No. 195,480.

This invention relates to finish members and more particularly to finish members for vehicle bodies for covering the protruding frame members and appurtenances carried thereby to produce a finished assembly with or without the presence of bumpers.

It is now quite generally the practice in vehicle constructions and particularly in motor vehicle constructions, to extend or project the ends of the vehicle frame forwardly and rearwardly of the body of the vehicle and to attach thereto the brackets or other fixtures by means of which the ends of the springs are attached and also by means of which the bumpers, if provided, are attached. Owing to the material of which the frame members and brackets are made, it is not customary nor convenient to provide these parts with a finish as attractive as or in keeping with the remainder of the vehicle. Furthermore in view of the character of the finish of these parts, dust, dirt and other foreign material more readily adheres thereto and thus makes it impractical to keep the appearance of this portion of the vehicle in keeping with the remainder.

More particularly, difficulty is experienced at the forward end of the vehicle in dislodging dirt, dust, and the like from the crevices and joints between the frame and the bumper bracket or spring shackle and from the spaces between the parts of the bracket and spring shackle. Furthermore the presence of these appurtenances add little, if anything, to the symmetry and finished appearance of the vehicle. Likewise at the rear end of the vehicle it is usually customary to arrange the gasoline tank between the protruding ends of the frame and to provide the ends of these frame members with bumper brackets and spring shackles. As a consequence difficulty is experienced at this point in cleaning the vehicle so as to dislodge the dirt which accumulates in the cracks and crevices.

One of the primary objects of this invention is to provide sheet metal finishing pieces entirely covering the exposed portions of the vehicle frame to thus produce a finished assembly with or without the bumpers being in place. These finishing pieces have downwardly extending portions overlying the ends of the frame and the outer faces of the bumper brackets and are held in place by the bumper when such equipment is em-

ployed. Members constituting fittings are provided and may be employed to secure the bumpers, if used, to the bumper brackets or may be arranged directly in engagement with the downwardly extending portions of the finishing members. These members enhance the decorative appearance of the finished assembly.

Another object of this invention is to provide finish members which will overlie the frame members and the appurtenances connected thereto or associated therewith, which members will cover and substantially conceal those parts which, by reason of the material of which they are made, are not given a finish equal to or consistent with the remainder of the vehicle. By this invention these finish members also provide means for substantially concealing the connection between the bumper brackets and frame members and between the frame members and the spring shackles and in addition provide a smooth surface which may be provided with a finish consistent with the remainder of the vehicle and which may as a consequence be readily cleaned and polished.

The several objects of this invention as well as an illustrative embodiment of the details of one example of the invention will be made more apparent as this description proceeds, especially when considered in connection with the accompanying drawings, wherein:

Figure 1 is a fragmentary top plan view of a portion of a vehicle frame with my invention associated therewith.

Figure 2 is a fragmentary side elevation of the structure illustrated in Figure 1.

Figure 3 is a view similar to Figure 1 of the rear portion of the vehicle frame member.

Figure 4 is a side elevation of the structure illustrated in Figure 3.

Figure 5 is a fragmentary front elevation showing a detail of the construction at the front of the vehicle, and

Figure 6 is a detail sectional view taken substantially on the plane indicated by line 6-6 in Figure 2.

Referring now particularly to the drawings wherein like reference characters indicate like parts, it will be noted that in Figures 1 and 2 there is illustrated fragmentarily one of the side frame members 10 of the vehicle provided with a protruding or pro-

jecting forward end 11 which extends beyond the radiator 12 of the vehicle. The reference character 13 indicates the engine hood and 14' the hood sill.

5 Attached to the forward end 11 of the frame member 10 is a bumper bracket 14 to which the bumper 15 is adapted to be connected.

The finish member at the front is provided by extending the hood sill 14' forwardly as indicated at 16 and shaping the same so that it is substantially U-shaped in cross section to thus provide a top 17 and downwardly extending side flanges 18. The 15 finish member is also provided with a downwardly extending portion or flange 19 at the forward end thereof. The finish strip is so located that the top 17 and sides 18 overlie the top and sides of the forward end 11 of 20 the frame member and the downwardly extending forward flange 19 overlies the forward face of the bracket 14 thus producing a finished assembly even without the bumper in place. The forward end 19 of 25 the finish member is preferably arranged contiguous to or in engagement with the front face of the bracket 14 and may be secured thereto by means of a fitting or plate member or members 20 secured in place by 30 bolts 21. The front fitting 20, as will be obvious, is duplicated at the forward end of both of the frame members and the inner face of each may be provided with a recess 35 22 for accommodating the inner horizontal bar of the bumper 15. When bumpers are not provided the fitting plates 20 are secured directly against the depending flanges 19 of the finish members but when the bumper 15 is employed the inner horizontal 40 bar of the bumper bears against the forward end 19 of each finish member to thus hold the finish member in place, and the finish plates 20 are then put into position, as indicated in Figures 1 and 2, and secured in 45 place by the bolts 21.

At the rear of the vehicle the protruding ends of the frame members are indicated by the reference character 23 and the gas tank, which is usually located between these frame member ends is indicated by the reference 50 character 24. One of the rear bumper brackets is indicated by the reference character 25 and 26 is the rear bumper. The finish strip is indicated generally by the reference 55 character 27 and comprises a top 28, sides 29 and a depending rear end 30 which overlies the face of the bumper brackets. The finish member overlies the tank 24, frame members 23 and brackets 25 and the depending end 30 extends between the bracket and the inner 60 bar of the bumper 26. The bumper is then secured in place by means of bolts or the like 31 which are the finish members equivalent to the finish plate 20 at the front of the vehicle. It is obvious that any desired or

more elaborate type of fittings may also be provided at the rear end as for instance, fitting plates such as employed at the front end. The bolts 31 or any other fittings may be secured to the brackets and directly engage the depending end 30 of the finish member when a bumper is not used thus producing a finished assembly with no bumper in place.

From the foregoing it will be readily apparent that in accordance with this invention a means is provided for producing a finished assembly, with or without bumpers and also for covering the protruding portions of the frame of the vehicle and the 70 brackets or other appurtenances carried thereby so as to conceal these parts. These finish members may be formed of sheet metal and conveniently provided with a surface which may be readily freed of dirt and dust and kept clean and polished consistent with the remainder of the vehicle.

While for the purpose of fully explaining the invention certain non-essential parts have been described somewhat in detail, nevertheless, it will be apparent to those skilled in the art that various changes in the non-essential details may be made without departing from the spirit and scope of this invention and to this end reservation is 95 made to make such changes as may come within the purview of the accompanying claims.

What I claim as my invention is:

1. The combination with a vehicle having 100 a protruding frame member, of a finish member overlying the top and end thereof and covering the exposed portions of said frame member.

2. The combination with a vehicle having 105 frame members protruding at the front and rear thereof, of sheet metal finish members extending over the top and downwardly over the ends of the protruding portions of said frame members.

3. The combination with protruding frame members of a vehicle and associated bumper supporting brackets, of finish members extending over said frame members and brackets and downwardly contiguous to the 115 faces of said brackets, as and for the purpose set forth.

4. The combination with protruding frame members of a vehicle and associated bumper supporting brackets, of finish members extending over said frame members and brackets and downwardly contiguous to the faces of said brackets and means for securing the downwardly extending portions to said bracket faces.

5. In a vehicle provided with a protruding frame member, a bracket secured thereto and a bumper supported by said bracket, the combination with these parts, of a finish member having a top, end and side portions 120

- and associated with the parts aforesaid whereby the top and side portions overlie the top and sides of said frame and the end portion extends between said bracket and 5 bumper.
6. In a vehicle provided with a protruding frame member, a bracket secured thereto and a bumper supported by said bracket, the combination with these parts, of a sheet 10 metal finish member having a top and depending sides and an end and associated with the parts aforesaid whereby said top and sides overlie said frame member and bracket and said end overlies the front face 15 of said bracket and extends between the latter and said bumper.
7. The combination with a vehicle having a forwardly projecting frame member and a hood sill, of a finish member formed by 20 extending said sill forwardly over said frame member, said finish member having a downwardly extending flanged end overlying the forward end of said frame member.
- 25 8. The combination with a vehicle having a forwardly projecting frame member, a bumper bracket secured to the forward end thereof and a hood sill, of a forward extension on said hood sill U-shaped in cross section to overlie said frame member and bracket and provided with a downturned forward end overlying the front face of said bracket to provide a finish member for said frame member and bracket.
- 30 9. The combination with a vehicle having a pair of rearwardly projecting frame members, a bumper bracket secured to the end of each and a tank arranged therebetween, of a finish member provided with a top and sides adapted to overlie said frame members and tank and a downturned end portion adapted to overlie the outer face of said bumper bracket.
- 35 10. The combination with a vehicle having protruding frame members and bumpers, of 45 finishing pieces shaped to entirely cover said frame members and held in place by said bumpers.
- 50 11. The combination with a vehicle having protruding frame members and bumper brackets secured thereto, of finishing members provided with downwardly extending portions overlying the outer faces of said
- brackets and producing a finished assembly.
12. The combination with a vehicle having 55 frame members protruding at the front and rear thereof, of finish members having portions extending downwardly and overlying the ends of the frame members to produce a finished assembly.
- 60 13. The combination with a vehicle having frame members protruding at the front and rear thereof, of finish members having portions extending downwardly and overlying the ends of the frame members to produce a 65 finished assembly and fittings engaging the outer face of said downwardly extending portions, as and for the purpose set forth.
14. The combination with a vehicle having protruding frame members and bumper 70 brackets secured thereto, of finishing members provided with downwardly extending portions overlying the outer faces of said brackets and producing a finished assembly and fittings, capable of attaching a bumper 75 in place, secured to said brackets in engagement with the outer face of said downwardly extending portions.
15. The combination with a vehicle having a protruding frame member and a 80 bracket secured thereto, of a finishing piece shaped to entirely cover said frame member and bracket and a fitting secured to said bracket for holding said finishing piece in place.
- 85 16. In a vehicle provided with a protruding frame member, a bumper bracket secured thereto and a bumper adapted to be secured to said bracket, the combination with said frame member and bracket, of a finishing 90 piece covering said parts and producing a finished assembly prior to the attachment of said bumper.
17. In a vehicle provided with a protruding frame member, a bumper bracket secured 95 thereto and a bumper adapted to be secured to said bracket, the combination with said frame member and bracket, of a finishing piece covering said parts and producing a 100 finished assembly prior to the attachment of said bumper, and a fitting, capable of attaching a bumper, secured to said bracket in engagement with said finishing piece.

In testimony whereof I affix my signature.

IVAN ORNBERG.
